UNITED STATES PATENT OFFICE.

HENRY C. HARDING, OF CHICAGO, ILLINOIS, ASSIGNOR OF ONE-HALF TO MADISON B. RUTHERFORD, OF CHICAGO, ILLINOIS.

PROCESS FOR APPLYING IODINE TO DISEASED AND INJURED PORTIONS OF THE BODY.

1,426,633.

Specification of Letters Patent. Patented Aug. 22, 1922.

Application filed December 13, 1918, Serial No. 266,553. Renewed January 14, 1922. Serial No. 529,370.

To all whom it may concern:

Be it known that I, HENRY C. HARDING, a citizen of the United States, residing at Chicago, in the county of Cook and State 5 of Illinois, have invented a certain new and useful Improvement in Processes for Applying Iodine to Diseased and Injured Portions of the Body, of which the following is a specification.

10 This invention relates to a process for applying iodine to diseased or injured portions of the body. Iodine has important medicinal properties and is of great therapeutic value. It is an important germicide. 15 It is ordinarily applied to the affected parts, in a liquid form, as a solution, the most common solution being that formed by dissolving iodine in alcohol. When thus used the affected part is painted with the solution and the alcohol quickly evaporates and 20 produces a discoloration at the place where it is applied, which lasts for days.

When used as a solution in alcohol only 25 a comparatively small amount of iodine is dissolved and when the alcohol evaporates most of the iodine stays on the surface and is not absorbed and cannot therefore be utilized. Another defect of such solution is 30 that it cannot be frequently applied, but can be applied only at considerable intervals, due to its irritating qualities.

My invention has among other objects to 35 provide a process of applying iodine which will obviate these defects and by means of which it can be applied in full strength and in such a form that it will be rapidly absorbed so that at the end of a few minutes there will be no discoloration and which will 40 also permit it to be applied at frequent intervals without injuring the skin or tissue, the application of the iodine being under complete control so that it may be easily and efficiently applied to any desired part.

45 I have illustrated in the drawings one form of apparatus for carrying out my process wherein

Fig. 1 is a side elevation of one form of such apparatus;

50 Fig. 2 is a sectional view therethrough;

Fig. 3 is a view showing a modified construction of the discharge end of the apparatus;

Fig. 4 is a view showing a further modi-

fied construction of the discharge end of 55 the apparatus.

Like numerals refer to like parts throughout the several figures.

The apparatus illustrated comprises a receptacle 1 for containing portions of the 60 iodine in solid form. This receptacle should be made of material which will withstand corroding action of the iodine such for example as copper. It is provided with an opening through which the iodine is inserted, the opening being closed by a suitable cover or cap 2. Some suitable means is provided for heating this receptacle so as to convert the iodine into a gas or fume. Any suitable means may be used for this purpose such for example as a flame of any kind. For purposes of illustration I have shown an alcohol lamp 3, the flame 4 of which heats the receptacle 1. Some suitable means is provided for directing the fume or 75 gas to or upon the part to be treated.

As herein shown I provide means for passing an air current through the top of the receptacle, which air current carries the fume or gas along with it, and by a suitable pipe or conductor this fume or gas is directed upon the part affected.

In the construction shown the receptacle is provided with a pipe 5 which communicates with the top of the receptacle. An air 85 moving device such as the elastic bulb 6 is connected with this pipe and is arranged so that when the bulb is squeezed, air is passed through the pipe 5 and through the top of the receptacle. A pipe 8 is also connected 90 with the top of the receptacle, preferably at the other side thereof, and this pipe is preferably connected with a flexible pipe 9. The pipes 5 and 8 may be made of rigid material such as metal. Pipe 9 may be made 95 of flexible material such as rubber. I may use the apparatus shown in Figs. 1 and 2 to carry out the process. As it is, I may if I desire attach to the end of the pipe 9 a nozzle 10 as shown in Fig. 3 having a contracted bent end 11, or I may simply use a straight nozzle 12, as shown in Fig. 4, having a contracted discharge end 13.

In carrying out the process I place the iodine in a solid form in the receptacle 1. 105 The receptacle is then closed and heat applied to it so as to convert the iodine into a fume or gas. The end of the tube 9 or

when the nozzles 10 and 12 are used, the contracted ends 11 and 13 thereof are placed in proximity to the surface to which it is desired to apply the iodine, the bulb 6 is then alternately compressed and relaxed, and a fume or gas is driven from receptacle 1 through the tubes 8 and 9, and when the nozzles are used, through the nozzles 10 and 12 and directed upon the place to which it is desired to apply the iodine. The fume or gas strikes the surface, where the iodine is to be applied and the iodine in its pure form is rapidly absorbed, thus thoroughly coming into contact with the parts affected or with the tissues in proximity thereto and is then absorbed into the blood. It will thus be seen that the application of the iodine is made under full control.

The fume is mixed with a current of air and this mixed air and iodine fume is forced, by having power applied thereto, to the point of use so that it strikes the surface to be treated, the iodine adhering thereto. When the particles of iodine are heated in this receptacle they are first melted and then converted into a fume or gas and it is this fume or gas that, by the controlled application, is applied to the surface upon which the iodine is to be used. When thus applied the surface to be treated is covered with the pure iodine and becomes discolored for a few minutes, the iodine becoming rapidly absorbed and the discoloration entirely disappearing in a short time. I have found that when applied in this manner the effective action of the iodine is greatly multiplied and its possibilities greatly increased. The iodine when thus used can also be applied repeatedly after short intervals of time without leaving any discoloration and without irritating the skin or membrane.

This cannot be done with the alcohol solution for with such solution the applications can only be after long intervals of time, as the irritating effect prevents frequent applications and the discoloration lasts for days. The small amount of iodine actually absorbed when such solution is used so limits the action as to prevent the iodine from being effective in many cases where remarkable effects are produced when the iodine is applied in its pure state in accord-

ance with this invention, such as in the treatment of a goiter, eczema, scrofula, acne and other skin diseases, tonsillitis, catarrh, 55 cuts, bruises and wounds. The iodine acts as a disinfectant and vitalizes the tissue, at the same time. It will thus be seen that the invention has a large and varied adaptability and use. 60

By converting the iodine into a fume and mixing it with air as herein set out it can be used in cavities of the body where it would be impossible to use an iodine solution. 65

I claim:

1. The process of applying iodine to diseased or injured parts of the body which consists in taking the iodine in a solid form, 70 converting it into a fume, and while in this form mixing it with a current of air and forcing the mixed air and iodine fume against the surface to be treated so that the iodine is condensed thereon.

2. The process of applying iodine to diseased or injured parts of the body which consists in taking the iodine in a solid form, 75 heating it sufficiently to convert it into a fume, then forcing this fume in a controlled 80 manner to the point where it is to be applied so that it will strike the surface to be treated and be condensed thereon.

3. The process of applying iodine to diseased or injured parts of the body which 85 consists in taking the iodine in a solid form, heating it until it melts and further heating it until it is converted into a fume, then mixing the fume with a relatively small current of air sufficient to carry the fume 90 along with it and then forcing this current of air and iodine fume in a relatively small stream to the point of use and then releasing the air and the iodine fume so that the air separates therefrom and the iodine is 95 deposited upon the surface to which it is to be applied.

In testimony whereof, I affix my signature in the presence of two witnesses this 5th day of December, 1918.

HENRY C. HARDING.
